UNITED STATES PATENT OFFICE.

ABBE SPRUNG, OF NEW YORK, N. Y.

SPARK-PLUG.

1,169,203.

Specification of Letters Patent.

Patented Jan. 25, 1916.

Application filed July 3, 1914. Serial No. 848,705.

To all whom it may concern:

Be it known that I, ABBE SPRUNG, a citizen of the United States, and a resident of New York, in the county and State of New York, have invented certain new and useful Improvements in Spark-Plugs, of which the following is a specification.

This invention relates to improvements in devices for producing electric sparks in connection with internal combustion engines and like mechanisms wherein explosive gases are ignited and which are commonly known as spark plugs.

The object of the invention is to provide a spark plug unusually simple and inexpensive in construction having a minimum number of parts and any number of sparking points desired.

A second object is to provide the insulating elements in multiple superimposed sections each carrying a section of the central electrode in such manner as to maintain the latter elements in positive intimate contact preventing arcing of the current at the junction of the insulating sections usually made of porcelain and to further provide means for avoiding danger of breaking the insulating elements through the transmission of heat.

A third object is to provide plugs in which the lower operative elements most subject to corrosion, damage and wear, are made interchangeable and hence readily removable from the main body or plug and at less expense than to install a wholly complete new plug.

These objects are accomplished by the novel construction and combination of parts hereinafter described and shown in the accompanying drawings, forming part of this specification, and in which:

Figure 1 is a partial side elevation and longitudinal section of a spark plug embodying the invention. Fig. 2 is a bottom plan view of the same. Fig. 3 is a side elevation of the upper porcelain or insulating element enveloping part of the central electrode. Fig. 4 is a similar view of the lower insulating element enveloping the lower section of the central electrode and, Fig. 5 is a side elevation of the sleeve used both as a supporting element for the insulator and as an adapter holding the sparking points of the opposite electrodes.

The main body of the spark plug com-

prises a screw threaded sleeve or casing 10 fitted to engage with the combustion chamber of an engine in which ignition is produced. Adjoining the sleeve is a shouldered collar 11 having its upper portion 12 formed to receive a wrench in applying the device in operative position. A dome shaped extension 13 rises thereabove and is provided with a circular opening 14 leading to an interior chamber 15 having at the upper edge a shoulder 16, the lower portion 17 being provided with an internal screw thread. Fitted to this chamber is a hollow sleeve or adapter 20, the lower part 21 of which is squared or otherwise fitted to receive a wrench, the upper end 22 being void of threads and used to support the insulator held therein. An insulator having a tapering body 25 and flanged enlargement 26 is passed through the opening 14 to which it is fitted, the enlarged base being suited to the chamber 15 and supported from the shoulder 16 by a flexible annular ring or washer 28.

Formed in the center of the base of the upper insulating element is a conical cavity 27 leading to a stepped conical recess 29, the cavity 27 containing the expanded end of the upper electrode, the same having a corresponding depression 30 formed integral with the stem 31 extending upward through the center of the upper insulator to a cap 32, the downturned portion 33 of which surrounds the upper end of the insulator and is provided with a threaded extension 34 to which terminal wires (not shown) for carrying an electric current, may be attached in any ordinary manner.

The lower insulating element is formed with a body 35 having an enlarged portion 36 freely fitting the chamber 15 and a conical extension 37 which registers with the cavity 27 in the upper insulator against which it is adapted to be pressed by the upper end 22 of the adapter.

An electrode having a metallic head 40, adapted to enter and make superficial contact with the cavity 30, with the main or upper electrode, extends above the flattened upper surface of the extension 37 and is provided with a downwardly extending stem 41, reaching normally to the end of the adapter head 21 and central with the opening therethrough. When the conical metallic head 40 is in contact with the interior

- of the conical cavity 30, a slight gap remains between the upper insulating element 25 and the lower insulating element 35, the purpose being to permit the insulating elements to expand by heat transmitted to them, and preventing electrical leakage, while between the enlarged flanged surfaces 26 and 36, is inserted a yielding washer 44 made of asbestos, fiber or other dielectric material and capable of being compressed as the insulating elements expand, thereby avoiding cracking of the porcelain elements and consequently their renewal for such cause.
- 15 Extending radially inward from the adapter are one or more opposite electrodes 43, the same being securely set in the adapter at the proper distance from center electrode stems 41, and, by reason of metallic contact 20 through the material of the adapter, convey an electric current from the opposite pole to the igniting points at the ends of the electrodes.

Whenever it is desirable to remove the 25 adapter to adjust or clean the points or dismount the device, it is evident that it can be done readily and quickly.

By reason of the peculiar arrangement of the electrodes and insulators, arcing or improper sparking cannot take place or leakage of the electric current and provision against breakage of both insulators and electrodes are fully provided.

Having thus described my invention and 35 ascertained its application and use, what I claim as new and desire to secure by Letters Patent, is:

1. In a spark plug, the combination with a chambered body, of an insulator therein 40 composed of upper and lower sections, the upper section extending above the confines of said body and having a conical cavity therein, the other section being suited to enter the mentioned cavity, electrode elements 45 extending through each section interengaging in the mentioned cavity and a sleeve containing other electrode elements screw-threaded into said chambered body.

2. In a spark plug, the combination with 50 a chambered body, of a sectional insulator therein, one section extending thereabove, enlarged bases formed with said sections, the upper section containing a conical cavity, the lower being suited thereto, electrode 55 elements extending through each section and interengaging in the cavity, a sleeve screw-threaded into said chambered body adapted to support and hold the electrode sections in electrical contact and maintain 60 said insulator in position within said body and one or more opposite pole electrodes secured in said sleeve, said opposite pole

electrodes extending radially within said sleeve and above the lower surface thereof.

3. In a spark plug, the combination with 65 a body having securing means and a chambered opening therethrough, of upper and lower insulating elements therein, said upper element having an axial depression in its base, the element extending unconfinely 70 above said body, the lower element being suited to the mentioned depression, an electrode, one section terminating in the upper insulating element and formed with a depression in its lower end, the other section 75 having a correspondingly shaped enlargement, means for maintaining said lower electrode and insulating element in position and one or more opposite pole electrodes carried by said means.

4. In a spark plug, the combination with 80 a body having securing means and a chambered opening therethrough, of upper and lower insulating elements therein, the upper element having a stepped conical depression in its base, the lower being provided with a conical projection flattened at its top, forming a seat, electrode elements so contained in the insulating elements as to maintain a space between the adjacent surfaces thereof, internal screw threads formed in the mentioned chamber opening in said body, a removable clamping means for said insulating elements, said clamping means 90 engaging with the screw-threads, and opposite pole electrodes rigidly set in said clamping means, in such manner as to be shielded thereby.

5. In a spark plug, the combination with a 95 hollow, chambered metallic body, of an insulator therein comprising two members having on their adjacent faces inter-engaging surfaces, compressible dielectric washers between portions of said surfaces and above the upper member thereof, an electrode in 100 each of said insulator members having metallic contact at their engaging ends, a sleeve surrounding the lower member of said insulator, said sleeve being adjustably engaged with said body and acting as a 110 clamping means for said insulator, opposite pole electrodes carried by said sleeve and a guard element for said electrodes formed with said sleeve, said guard element extending below the lowermost plane of said electrodes.

In witness whereof I have signed my name to this specification in the presence of two subscribing witnesses.

ABBE SPRUNG.
